(57) **CLAIM**

The ornamental design for portable dispenser for wound rope material, as shown and described.

DESCRIPTION

FIG. 1 is a perspective view of the portable dispenser for wound rope material showing our new design.

FIG. 2 is a right side elevation view of FIG. 1;

FIG. 3 is a rear elevational view of FIG. 1;

FIG. 4 is another perspective view taken from a different angle than FIG. 1;

FIG. 5 is a top view of FIG. 1; and,

FIG. 6 is a front elevational view of FIG. 1.
